UNITED STATES PATENT OFFICE.

JOHN McGRANIGHAN, OF ROXBORO, PHILADELPHIA, PENNSYLVANIA.

RAILWAY-TIE.

No. 806,358.

Specification of Letters Patent.

Patented Dec. 5, 1905.

Application filed July 29, 1905. Serial No. 271,727.

To all whom it may concern:

Be it known that I, JOHN McGRANIGHAN, a citizen of the United States, residing at Roxboro, in the county of Philadelphia and State 5 of Pennsylvania, have invented certain Improvements in Railway-Ties, of which the following is a specification.

This invention relates to the use of stone blocks for supporting railway-rails; and it has 10 for its leading purpose the production of improved means for the application of such blocks to supporting the rails and for connecting them together in the form of a tie, whereby there is provided a strong and enduring structure which can be constructed, assembled, and 15 removed at a comparatively small cost.

In the accompanying drawings, Figure 1 is a plan view of my improved tie. Fig. 2 is a side elevation thereof. Fig. 3 is a side elevation 20 of the half of a modified form of tie, and Fig. 4 is a plan view of a structure similar to and to be joined with that shown in Fig. 3 to form a tie.

In Figs. 1 and 2 of the drawings granite or 25 other stone blocks 1, having the battered sides 1', are each provided with a metal band or strap 2 on the bottom and a metal band or strap 3 on the top thereof. Each of the bottom straps has a twist 2' therein adjacent to 30 the inner end of the block to which it is attached, and projecting inwardly therefrom a vertically-disposed part 2'', lying in a plane at right angles to the main portion of the strap engaging the bottom of the block. Each of 35 the top straps has its outer end turned back to form a hook or catch 3' and is provided with a twist 3'' adjacent to the inner end of the block to which it is attached, beyond which extends downwardly and inwardly a projecting portion 3'', disposed in a vertical plane at right angles to the horizontally-disposed main 40 portion of the strap engaging the top of the block and overlapping the corresponding projection 2''. Bolts 4 pass through the respective blocks and the straps thereon to hold 45 these parts together and to clamp thereto the clips 5 for engaging the inner flanges 6' of the rails 6, the corresponding outer flanges of the rails being engaged by the hook strap ends 3'.

The rails thus secured to the blocks are tied 50 together by the overlapping band ends 2'' and 3'', through which are passed the bolts 7.

In the modified construction shown in Figs. 3 and 4 of the drawings the stone blocks 1 have thereon the wooden block 8, through 55 which and the straps 2 and 3 pass the bolts 4 for clamping the clips 5 upon the respective flanges 6' of the rails 6, the ends of the straps 2 being provided, respectively, with the twists 2' and overlapping extensions 2'' and the ends 60 of the strap 3 being provided, respectively, with the twists 3'' and the extensions 3''' overlapping the extensions 2'', these parts being bolted together, as previously described.

Having described my invention, I claim— 65

1. In a railway-tie, in combination with rails, blocks for supporting said rails, a bottom strap secured to each block for connecting them together, and a top strap secured to 70 each block and having means for engaging and holding said rail, substantially as specified.

2. In a railway-tie, in combination with rails, blocks for supporting said rails, top and bottom straps secured to said blocks and connected together, and means whereby said top 75 straps engage and hold said rails, substantially as specified.

3. In a railway-tie, in combination with rails, blocks for supporting said rails, and top and bottom straps attached thereto and connected together, said top straps having hooks thereon for engaging said rails, substantially 80 as specified.

4. In a railway-tie, in combination with rails, blocks for supporting said rails, and 85 straps secured together and to the tops and bottoms of said blocks, said straps having twists therein providing for horizontally-disposed portions to engage said blocks and vertically-disposed portions to engage said straps 90 together, substantially as specified.

In testimony whereof I have hereunto set my hand, this 27th day of July, 1905, in the presence of the subscribing witnesses.

JOHN McGRANIGHAN.
